FISHHOOK TYING FIXTURE

Leonard D. Graber, Rte. 1, Moundridge, Kans. 67107

Filed June 6, 1969, Ser. No. 17,547

Term of patent 14 years

Int. Cl. D22—08

U.S. Cl. D22—31

Fig. 4.

Fig. 2.

Fig. 1.

Fig. 3.

Fig. 5.

Fig. 6.

Fig. 8.

Fig. 7.

FIG. 1 is a side elevational view of one embodiment of the fishhook tying fixture;

FIG. 2 is an elevational view of one end thereof;

FIG. 3 is an elevational view of the opposite end thereof;

FIG. 4 is a top plan view thereof;

FIG. 5 is a perspective view of another embodiment of the fishhook tying fixture;

FIG. 6 is a side elevational view thereof;

FIG. 7 is an elevational view of one end thereof;

FIG. 8 is an end elevational view of the opposite end thereof.

I claim:

The ornamental design for a fishhook tying fixture, substantially as shown and described.
